US00D850316S

(12) **United States Design Patent** (10) **Patent No.:** **US D850,316 S**
(45) **Date of Patent:** **** Jun. 4, 2019**

(54) **VIR BAND**

(71) Applicant: **Precision Dynamics Corporation**, Valencia, CA (US)

(72) Inventors: **Ronald G. Ennis**, Los Angeles, CA (US); **Jonathan F. Trachtman**, Tujunga, CA (US)

(73) Assignee: **Precision Dynamics Corporation**, Valencia, CA (US)

(**) Term: **15 Years**

(21) Appl. No.: **29/604,939**

(22) Filed: **May 22, 2017**

(51) LOC (11) Cl. **11-01**

(52) U.S. Cl. **D11/3**
USPC ....

(57) **CLAIM**

The ornamental design for a VIR band, as shown and described.

DESCRIPTION

FIG. 1 is a top, front, and left perspective view of a VIR band according to the present design;

FIG. 2 is a left elevational view of the VIR band of FIG. 1;

FIG. 3 is a top plan view of the VIR band of FIG. 1;

FIG. 4 is a rear elevational view of the VIR band of FIG. 1;

FIG. 5 is a front elevational view of the VIR band of FIG. 1;

FIG. 6 is a right elevational side view of the VIR band of FIG. 1;

FIG. 7 is a bottom plan view of the VIR band of FIG. 1; and, FIG. 8 is cross-sectional left side view of the VIR band of FIG. 1 taken through line 8-8 of FIG. 3.

The broken lines shown in the drawings illustrate portions of the VIR Band that form no part of the claimed design. The VIR Band is shown with symbolic break lines in its length. The appearance of any portion of the article between the break lines forms no part of the claimed design.

1 Claim, 3 Drawing Sheets
